UNITED STATES PATENT OFFICE.

GEORGE H. PEMBROKE, OF NEW BRUNSWICK, NEW JERSEY, ASSIGNOR TO MARCUS H. HORTON, OF BROOKLYN, NEW YORK.

PAPER-FASTENING MACHINE.

1,195,718.

Specification of Letters Patent. Patented Aug. 22, 1916.

Application filed December 31, 1912. Serial No. 739,428.

To all whom it may concern:

Be it known that I, GEORGE H. PEMBROKE, a citizen of the United States, residing at New Brunswick, Middlesex county, in the 5 State of New Jersey, have invented certain new and useful Improvements in Paper-Fastening Machines, of which the following is a full, clear, and exact specification.

My invention relates to improvements in 10 means for fastening and binding together sheets of paper or analogous articles by means of an eyelet, and the same has for its object more particularly to provide a simple, efficient and reliable apparatus which is compact in form, simple and positive in operation and not liable to get out of order.

Further said invention has for its object to provide a machine for the purposes specified which is designed to receive a series of 20 fastening members mounted upon a suitable support, and then feed the same, one by one, to the driving mechanism whereby the said fasteners are caused to secure the paper together.

25 Further said invention has for its object to provide a machine in which the fastener in position to be driven will remain properly in such position until it is actually driven, and will not feed another fastener into operative position until the first fastener has 30 been actually driven into the paper or otherwise disposed of.

Further said invention has for its object to provide a machine for the purposes specified which shall be compact in form, simple in construction and so arranged that access may be had to the interior thereof for the purpose of adjustment and cleaning.

To the attainment of the aforesaid objects and ends my invention consists in the 40 novel details of construction, and in the combination, connection and arrangement of parts hereinafter more fully described and then pointed out in the claims.

45 In the accompanying drawings forming a part of this specification wherein like numerals of reference indicate like parts, Figure 1 is a side view showing one form of machine constructed according to and embodying my said invention; Fig. 2 is a vertical section taken substantially on the line 2-2 of Fig. 1 showing the machine with a fastener in position ready to be driven; Fig. 3 is a similar view showing the fastener 55 driven or just about to be riveted to fasten

the paper together; Fig. 4 is a similar view showing the parts in their retracted position and about to engage a fastener for subsequent driving; Fig. 5 is a detail vertical section taken essentially on the line 5-5 of Fig. 2; Fig. 6 is an enlarged detail side view partly in section showing the lower part of a supporting rod and the lowermost eyelets in position thereon, Fig. 7 is a detail perspective view showing the construction of the lower ends of the chuck jaws.

In said drawings 10 designates the machine as a whole comprising a base 11 from which projects a standard 12. 13 denotes a cylindrical section which is rigidly secured to the standard or upright 12 by screws 13^a, 13^b. Within the casing 13 is secured a head 14 having a flange 15 thereon resting upon the upper edge of the casing 13. The head 14 is provided with a circular opening having its inner lower portion beveled at 16.

17 denotes a thumb screw which extends through the upper end of the upright or standard 12 and engages the inclosed portion of the head 14 whereby to secure said 20 head firmly in position within the top of the casing 13 and maintain the operating parts within said casing duly in position therein.

18 denotes a shaft which is disposed within the opening in the head 14. The said shaft 18 is provided at its upper end with an operating head 19, and at its lower end with a reduced portion 20.

21 denotes a longitudinal groove provided in the shaft 18 through which extends a pin 22 having its inner end secured to a tubular section 23 slidably mounted within the shaft 18.

The head 14 is provided at its forward portion with a vertical recess 24 in the base of which is vertically secured an adjusting screw 25 whose upper end serves as a support for the forward end of the pin 22 carried by the tubular section 23, and to limit the downward movement of said tubular section within the shaft 18.

26 denotes a yoke secured in the upper side of the head 14 which embraces the pin 22 and serves to limit the upward movement of the tubular section 23 when the shaft 18 and head 19 are drawn upwardly.

27 denotes a support which is substantially circular in outline and secured to the reduced shaft portion 20 adjacent to its 110

lower end by means of a screw 27^a. The said support 27 is provided at its opposite sides with vertical recesses 28, 28 within which are vertically disposed jaws 29, 29 which are pivotally mounted upon pins 30, 30 carried by said support. The upper ends of said jaws 29, 29 are beveled in order to engage with the beveled surface 16 of the head 14, and the lower ends of said jaws 29 are arranged at substantially right angles to the vertical portions thereof and have their opposing edges recessed to form a socket for an eyelet, and also a passage for the rod or support for the eyelets.

31 denotes an annular member or carrier disposed within the lower end of the casing 13 and provided at its opposite sides with pins 32, 32 which extend through recesses 33, 33 provided in the casing 13. Upon the outer opposite sides of the casing 13 are secured guide plates 34, 34, and upon the outer sides of the casing 13 but within said guide plates 34, 34 are secured pins 35, 35.

36, 36 denote springs secured at their upper ends to the pins 35, 35 arranged upon the outer side of the casing 13, and at their lower ends to the pins 32, 32 secured to the annular member or carrier 31.

The annular member 31 has its inner surface rounded at 37 to act as a cam when the rounded portions of the jaws 29, 29 are brought into contact therewith and serves to cause the ends of said jaws to be guided into engagement with each other and to embrace the eyelets and the rod therefor.

The base 11 is provided at its center with a socket into which is fitted an anvil 38 having an upwardly projecting pin or stud 39 and an annularly grooved base 40 surrounding said pin or stud 39 which serves to turn the lower edge of an eyelet outwardly when the eyelet is forced thereon by means of the jaws 29, 29.

The operation of the apparatus is as follows: The eyelets for use in connection with the machine are mounted upon a rod 41 which is provided at its upper end with a ring or finger portion 42 adapted to rest upon the upper end of the tubular section 23 in order to prevent the lower end of said rod coming in contact with the pin or stud 39. The said rod 41 is of such diameter that the tubular portions 43 of the eyelets will slide freely thereon while the lower end of the rod 41 is provided with a slight bur or head of such size as to be just sufficient to prevent the tubular portion of the eyelets 43 passing freely thereover. By this means the lowermost eyelet upon the rod 41 will be held duly in position upon the said rod ready for driving.

In order to drive an eyelet, the shaft 18 must first be drawn upwardly by means of its head 19 until the pin 22 on the tubular section 23 within said shaft 18 engages the

yoke 26 and prevents further movement of said shaft 18 and tubular section 23. At the same time the upper beveled ends of the jaws 29 will be brought into contact with the inner beveled edge 16 of the head 14, and cause the lower ends of the jaws to become separated and assume the position indicated at Fig. 4. As soon as the lower ends of the jaws 29 have become thus separated the rod 41, with the eyelets thereon, will be permitted to drop sufficiently to allow the lowermost of said eyelets to be brought into position directly below the lower edges of the horizontal portions of the jaws 29, 29 whereupon said jaws are caused to be brought together with the succeeding downward movement of the shaft 18, and connected parts due particularly to the engagement of the rounded portions of the jaws 29, 29 with the inner rounded surface 85 of the annular member 31. With this movement of the shaft 18, and the parts carried thereon, the apparatus will be in the position indicated at Fig. 2.

In order to drive the fastener into the paper or other article to be joined together it simply becomes necessary to strike upon the surface of the head 19 a sharp blow with the hand and thereby cause the shaft 18 and its reduced portion 20 together with the support 27 to be driven downwardly and the annular member 31 to be carried downwardly at the same time in opposition to the tension of the supporting springs 36, 36.

As soon as the lower edge of the tubular portion of the eyelet strikes the grooved base 40 of the anvil 38 the lower edge of said tubular portion will be flared outwardly and the eyelet caused to clamp the paper or material between the flange 43^a of said eyelet and the newly formed flange at the lower edge thereof.

Should the machine for any reason fail to rivet the eyelet with the first impact the parts will be caused to resume the position indicated at Fig. 2, that is to say, the lowermost eyelet on the rod 41 will remain in position below the horizontal portions of the jaws 29, 29 and prevent the feeding of the succeeding one. The shaft 18 and parts carried thereon may thereupon be forced downwardly again by a sharp blow with the hand upon the upper surface of the head 19, and the eyelet riveted.

In order to bring the succeeding eyelet in position for driving it is first necessary to raise the shaft 18 by means of its head 19, as first above described, to separate the lower ends of the jaws to permit the entire stack of eyelets upon the rod 41 and said rod to drop the required distance.

Having thus described my said invention what I claim and desire to secure by Letters Patent is:—

1. A machine of the character described

comprising a base, a casing thereon, a chuck in said casing, a fastener-supporting member loosely supported within said chuck, and means for actuating said chuck to remove a 5 fastener from said fastener-supporting member and drive the same, substantially as specified.

2. A machine of the character described comprising a base, a casing thereon, a chuck

10 in said casing, a separate fastener-supporting member loosely supported in vertical position within said chuck, and means for actuating said chuck to engage a fastener at the lower end of said fastener-supporting member and drive the same, substantially as specified.

15 3. A machine of the character described comprising a base, a casing thereon, a chuck in said casing, a separate fastener-supporting member disposed within said chuck and supported at its upper end, and means for actuating said chuck to remove a fastener from the free end of said fastener-supporting member and drive the same, substantially as specified.

20 4. A machine of the character described comprising a base, a casing thereon, a chuck in said casing, a fastener-supporting rod disposed within said chuck and provided 25 at its upper end with means for suspending the same within said chuck, and means for actuating said chuck to remove a fastener from the free end of said rod, substantially as specified.

25 5. A machine of the character described comprising a base, a casing thereon, a chuck in said casing, a fastener-supporting rod on said chuck provided at its upper end with means for suspending the same therein, and means for actuating said chuck to remove a fastener from the free end thereof and drive the same, substantially as specified.

30 6. A machine of the character described comprising a base, a casing thereon, a chuck in said casing, a fastener-supporting rod disposed within said chuck, a head at the upper end of said fastener-supporting rod for suspending the same within said chuck, and means for actuating said chuck to remove a fastener from the free end of said rod and drive the same, substantially as specified.

35 7. A machine of the character described comprising a base, a casing thereon, a chuck in said casing, means for yieldingly supporting said chuck within said casing, a fastener-supporting rod suspended within said chuck, and means for actuating said chuck to remove a fastener from the free end thereof and drive the same, substantially as specified.

40 8. A machine of the character described comprising a base, a casing thereon, a chuck in said casing embodying a pair of piv-

otally mounted jaws, means for yieldingly supporting said chuck, a fastener-supporting member suspended within said chuck, means for actuating said chuck to cause the jaws thereon to engage a fastener and to hold the same in position for driving, and means for actuating said chuck to drive said fastener, substantially as specified.

45 9. A machine of the character described comprising a base, a casing thereon, a chuck in said casing embodying a pair of piv- 75 otally mounted jaws, a member suspended intermediate said jaws, fasteners disposed upon said member, means for actuating said jaws to engage a fastener and to hold the 80 same in position for driving, and means for actuating said chuck to drive a fastener, substantially as specified.

50 10. A machine of the character described comprising a base, a casing thereon, a chuck in said casing embodying a pair of piv- 85 otally mounted jaws, means for yieldingly supporting said chuck, a fastener-supporting member suspended intermediate said jaws, means for actuating said jaws to en- 90 gage a fastener and to hold the same in position for driving, and means for actuating said chuck to drive a fastener, substantially as specified.

55 11. A machine of the character described comprising a base, a casing thereon, a chuck in said casing embodying a pair of piv- 95 otally mounted jaws, means for yieldingly supporting said chuck, means for maintaining the free ends of said jaws normally 100 separated, a fastener-supporting member suspended intermediate said jaws, means for actuating said jaws to cause the free ends thereof to engage a fastener and to hold the same in position for driving, and 105 means for actuating said chuck to drive a fastener, substantially as specified.

60 12. A machine of the character described comprising a base, a casing thereon, a chuck in said casing embodying a pair of piv- 110 otally mounted jaws, a fastener-supporting member having its upper end supported in said chuck and its lower end free, means for actuating said jaws to engage a fastener at the end of said supporting member and 115 to hold the same in position for driving, and means for actuating said chuck to drive a fastener, substantially as specified.

65 13. A machine of the character described comprising a base, a casing thereon, a chuck 120 arranged in said casing embodying a pair of pivoted jaws, cam means for opening said jaws, fastener supporting means carried by said chuck, means for yieldingly supporting said chuck and connected parts, 125 cam means for closing said jaws and maintaining the same in position for driving a fastener, and means for actuating said chuck to drive said fastener, substantially as specified.

14. A machine of the character described comprising a base, a casing supported above said base, a head fixed in the upper end of said casing, a vertical shaft guided on said head, a chuck carried by said shaft; said chuck embodying a pair of pivoted jaws, a carrier movably arranged in said casing for supporting said shaft and chuck, spring means for maintaining said carrier normally elevated and said jaws normally closed, means for actuating said jaws to feed a fastener into position for driving, and means for actuating said chuck to drive said fastener, substantially as specified. 50
15. A machine of the character described comprising a base, a casing supported above said base, a head fixed in the upper end of said casing, a vertical shaft guided on said head, a chuck carried by said shaft; said chuck embodying a pair of pivoted jaws, a carrier movably arranged in said casing for supporting said shaft and chuck, means for guiding said chuck in its up and down movements, spring means for maintaining said carrier normally elevated and said jaws normally closed, cam means for actuating said jaws to feed a fastener into position for driving, and means for actuating said chuck to drive said fastener, substantially as specified. 65
16. A machine of the character described comprising a base, a casing supported thereon above said base, a head rigidly secured in the upper end of said casing, a vertical shaft guided in said head, an operating head secured to the upper end thereof, a chuck carried by the lower end of said shaft comprising a support secured to the lower end of said shaft, a pair of jaws pivotally mounted in said support, a carrier arranged in the lower end of said casing and engaging the lower ends of said jaws for supporting said jaws, support therefor and shaft, spring means for sustaining said carrier and the parts carried thereby in a normally elevated position, fastener supporting means movably disposed within said shaft, and means for limiting the movement of said shaft and fastener supporting means therein, substantially as specified. 70
17. A machine of the character described comprising a base, a cylindrical casing mounted thereon having longitudinal recesses therein, a head secured in the upper end of said casing, cam means provided upon the underside thereof, a tubular shaft movably disposed on said head and provided with a longitudinal slot, an operating head at the upper end of said shaft, a tubular eyelet supporting section loosely 60 fitted within said tubular shaft, a pin secured to said tubular section and extending through the longitudinal slot in said tubular shaft, means provided upon said head for limiting the movement of said pin and said tubular eyelet supporting section, a support secured to said tubular shaft adjacent to its lower end, a pair of jaws pivotally secured to said head and having their upper ends beveled and adapted to engage with the cam 75 means on the under side of said head, and their lower ends arranged at substantially right angles to the body portions thereof and provided in their opposing edges with recesses, an annular member disposed in 80 said casing below said jaws and provided with an inclined inner surface, pins projecting from said annular member and extending through the recesses in said casing, springs secured at their upper ends to said casing, and at their lower ends to the pins on said annular member for yieldingly supporting said annular member and the parts carried thereby, and an anvil arranged upon said base, substantially as specified. 85

Signed at the city of New York, in the county and State of New York, this nineteenth day of December, one thousand nine hundred and twelve.

GEORGE H. PEMBROKE.
